UNITED STATES PATENT OFFICE.

HOWARD F. SNYDER, OF NEWTON, IOWA, ASSIGNOR TO THE MAYTAG CO., OF NEWTON, IOWA.

GEAR MECHANISM.

1,117,268.

Specification of Letters Patent. Patented Nov. 17, 1914.

Application filed May 13, 1911. Serial No. 627,074.

To all whom it may concern:

Be it known that I, HOWARD F. SNYDER, a citizen of the United States, residing at Newton, in the county of Jasper and State of Iowa, have invented a new and useful Improvement in Gear Mechanisms, of which the following is a specification.

My invention relates to mechanisms for transmitting the rotary motion of a power shaft to various operating shafts and its object is to provide a gear mechanism carried by a suitable support for transmitting the movement of a power driven shaft to one or more operating shafts, also mounted on this support.

As my invention is particularly useful in connection with power driven washing machines, I have illustrated my invention in the accompanying drawings as applied to a washing machine, although I would have it understood that it is not limited to such use.

One object of my invention is to mount a horizontal shaft on a suitable support so as to swing bodily in a horizontal plane toward and away from the support without breaking operative connection with the associated transmitting shaft, also carried by the support. This transmitting shaft is adapted to be operated from a power shaft which, in the preferred embodiment of my invention, is mounted below the support which carries the different parts of the mechanism. When my invention is applied to a washing machine this horizontal swinging shaft is the wringer shaft and the swinging frame-work which supports this shaft is the frame-work of the wringer. The purpose of the horizontally swinging wringer frame is to permit use of the wringer in two positions—one against the support or tub of the washing machine, and the other at approximately right angles to the first position. In the first position the wringer is used to wring the clothes from the tub of the washing machine into a wash tub or suitable receptacle placed beside the machine. In the second position the wringer is used to wring the clothes from one tub into the other, while the washing machine is operated in the usual manner with the cover closed.

Another object of my invention is to provide means whereby the clutch which establishes operative connection between a pair of shafts carried on the support is automatically controlled by the movement of a

hinged member on the support. When my improved gear mechanism is applied to a washing machine this hinged member is the top or cover for the tub, and the clutch which the cover controls throws the horizontal or wringer shaft into and out of operation. When the hinged member or cover is in closed position, the clutch referred to is open, and it remains open until the cover is moved into open position, whereupon the clutch is automatically actuated into closed position. In order to permit of the operation of the horizontal or wringer shaft even when the hinged member is closed, I have provided independent hand-controlled means for moving the clutch into closed position. In this way the horizontally swinging shaft may be clutched in when swung outwardly at right angles to the support, with the cover or hinged member in closed position, and the machine operated as usual.

A further object of my invention is to provide a motor support or frame which is adapted to be readily slipped on and off the power shaft to make or break connection between the pinion on the motor shaft and the driving gear on the power shaft. No fastening devices are necessary to hold the support or frame for the motor in operative position, the frame resting by gravity on a suitable bracket fixed to the support which carries my improved gear mechanism.

The above and other objects and advantages of my invention will become apparent from a detailed description of the accompanying drawings in which—

Figure 1 is a side elevation of my improved gear mechanism, the same being, for the sake of illustration, shown as applied to a washing machine, the latter being shown in cross-section for the sake of clearness; Fig. 2 is a side elevation of my improved gear mechanism, certain of the parts being, for the sake of clearness, shown in cross-section; Fig. 3 is a detailed view showing how the clutch which controls the operation of the horizontal or wringer shaft may be operated independently of the hinged member which normally determines the position of the clutch; Fig. 4 is a view similar to Fig. 3 showing the control of the clutch by the hinged member, the latter being shown in open position and the clutch in closed position; Fig. 5 is a plan view of Fig. 1, the horizontally swinging frame-work being

shown in full lines in its normal position against the support, and in dotted lines in its outwardly swung position away from the support; Fig. 6 is a fragmentary detailed view in plan showing the pivotal connection 5 between the motor frame and the power shaft; Fig. 7 is a view at right angles to Fig. 1 looking from left to right, the gear casting being, for the sake of clearness, shown in cross-section; Fig. 8 is a fragmentary detailed view of certain connections 10 shown in Figs. 3 and 4; and Fig. 9 is a fragmentary detailed view partly in cross-section showing a simple means for clamping the horizontally swinging frame-work into 15 any adjusted position.

In the accompanying drawings the support for my improved gear mechanism is, for the sake of illustration, shown in the 20 form of a washing machine tub 1 provided with legs 2 which are connected together by cross braces 3. If desired, an additional reinforcing rod 4 may be used between one or both pairs of legs. The top of the support 1 is provided with a cover 5 which is 25 pivoted to the tub or support 1 by means of hinges 6 so as to swing in a vertical plane. The part 5 will hereinafter be broadly referred to as a hinged member.

To the side of the support 1 is secured a 30 casting indicated as a whole by C which comprises a main vertical body portion 7, an upper or head portion 8 and a bell-shaped enlargement 9 at the lower end. The casting is provided with lateral lugs or flanges 35 9^a at the upper and lower ends, as shown in Fig. 7, for receiving suitable fastening devices, such as bolts 9^b. If desired the head 8 of the casting may be provided with a 40 horizontal extension 8^a adapted to rest on top of the support 1. A bolt 8^b may be passed through the horizontal extension 8^a and the support 1 as additional securing means for the casting C. The head portion 45 8 is provided with a bearing opening 10, while a bearing opening 11 is formed at the lower end of the main portion 7. The openings 10 and 11 are in vertical alinement with each other and provide journal bearings for 50 the vertical transmission shaft 12. To the upper end of this shaft is fixed the crank member 13 which, in the drawings, is shown in the form of a disk carrying a crank pin 14 at the outer edge thereof. The crank member 13 is provided with a hub 15 which 55 rests upon the head portion 8 of the casting C and assists in holding the shaft against downward movement in its journal bearings. To the lower end of the shaft 12 is 60 secured a horizontal bevel gear 16 which is arranged to mesh with a pair of bevel pinions 17 and 18, rotatably mounted on the power shaft 19. The horizontal gear 16 and the associated vertical pinions 17 and 18 are 65 housed with the bell-shaped enlargement 9

of the casting C. This enlargement is provided with diametrically opposite bearings 20 in which the power shaft 19 is rotatably supported. The bevel pinions 17 and 18 engage the horizontal bevel gear 16 at diametrically opposite points so that the direction of rotation of the transmission shaft 12 depends upon which one of the two bevel pinions is operatively connected to the power shaft which is driven continuously in 70 one direction by an electric motor or equivalent power device. The bevel pinion 17 has fixed thereto a clutch sleeve 17^a, while the other bevel pinion 18 is provided with a similar clutch sleeve 18^a. The clutch sleeves 17^a and 18^a form parts of a double-throw clutch mechanism of which the main reciprocating member is the sleeve 22 slidably keyed upon the power shaft 19. When this main sleeve 22 is in its neutral or midway 85 position, as shown in Fig. 2, both of the pinions 17 and 18 remain idle on the shaft 19. When the clutch sleeve 22 is moved into operative engagement with the sleeve 17^a, the bevel pinion 17 becomes coupled to the power shaft 19 and the transmission shaft 12 is rotated in one direction. When the clutch sleeve 22 is moved into engagement with the sleeve 18^a, the bevel pinion 18 becomes operatively connected to the power 90 shaft 19 and the transmission shaft 12 is rotated in a reverse direction. The power shaft 19 has fixed thereto the large gear 23 which is permanently in mesh with the pinion 24 secured upon the shaft of the electric 95 motor M. The frame 25 on which the motor is mounted is provided with bearing lugs 26 through which the power shaft 19 passes, as best shown in Fig. 6. The motor M is rigidly attached to the base portion of the 10 frame 25 by bolts or other fastening devices 27. The frame 25 has on its under surface a rib 28 which engages the vertical bracket 29 secured to one of the cross braces 3 by means of bolts or rivets 30. The base portion of the frame 25 is thus normally held in a substantially horizontal position. It will be observed that the motor frame or support 25 may be readily slipped on to the power shaft 19 so as to bring the motor pinion 24 11 into mesh with the main driving gear 23. A cotter 31 or other suitable device engages one of the bearing lugs 26 to prevent lateral movement of the motor frame 25 on the power shaft 19. By simply withdrawing 12 the cotter 31, the motor and its supporting frame may be entirely withdrawn from the support which carries the gear mechanism of my invention. When the motor frame is in operative position, no fastening devices 13 are necessary to retain it in this position, the frame resting by gravity on the bracket 29. Since the power shaft 19 forms a pivotal support for the motor frame it is impossible for the gear members 23 and 24 to 14

get out of mesh or to bind when the motor is operatively associated with the power shaft 19. The direction of operation of the motor M is indicated by the arrow *a* in Fig. 7.

I will now describe the means for controlling the clutch member 22 for operatively connecting one or the other of the pinions 17 or 18 with the power shaft 19. The bell-shaped enlargement at the lower end of the casting C is provided with a pair of diametrically opposite lugs 32 which carry the shaft 33. Cotters 34 prevent the shaft 33 from moving longitudinally in the supporting lugs 32. A bracket 35 is slidably mounted on the shaft 33 by means of perforated arms 36 through which the shaft passes. One of the arms 36 is provided with a yoke-shaped extension 37 arranged to engage in the annular recess 38 formed on the clutch member 22 by means of a pair of spaced shoulders 39. To the side of the support 1 opposite from the casting C is secured a pair of bearing brackets 40 for rotatably supporting the vertical crank shaft 41. The upper end of this crank shaft has a handle 42, while the lower end terminates in a crank arm 43. A connecting link or bar 44 is at one end pivotally connected to the bracket 35 by means of the stud or pin 45, while the other end of the bar 44 is pivotally connected to the crank arm 43 of the shaft 41. The connecting link or bar 44 is suitably bent so as to pass below the gear wheel 24 and out of the way of the motor supporting frame 25. The handle 42 on the crank shaft 41 is provided with a ridged latching surface 46 adapted to coöperate with a latch plate 47 fixed upon the hinged member 5 for locking the same in closed position. When the handle 42 is in the position shown in Fig. 1, the hinged member 5 is locked and the clutch member 22 is operatively connected to the pinion 17. This causes rotation of the vertical transmission shaft 12 in a certain direction. When the handle 42 is moved at right angles to the position shown in Fig. 1, the clutch member 22 is in its neutral or midway position, as shown in Fig. 2. In this position of the clutch member, both of the pinions 17 and 18 are idle during the rotation of the power shaft 19. When the handle 42 is turned 180° from the position shown in Fig. 1, the crank arm 43 will occupy the position indicated in dotted lines at 43^a in Fig. 1 and the clutch member 22 is in operative engagement with the pinion 18, so that the transmission shaft 12 now rotates in a direction reverse to that in which it operated when the handle was in the position shown in Fig. 1. It will be observed that when the clutch member 22 is in either one of the operative positions, the hinged member 5 is locked in its normally closed position. To hold the ridged latching surface

46 of the handle 42 in firm engagement with the latch plate 47, a coil spring 48 is provided on the crank shaft 41. The upper end of the spring bears against the bracket 40 and the lower against a pin or stud 49 on the shaft 41. The tendency of the spring 48 is to force the shaft 41 downwardly, so that the ridged locking surface 46 snaps into the notch 50 provided on the latch plate 47 when the handle 42 is in latching position. When the handle 42 is in open position the shaft 12 is essentially disconnected from the power shaft 19. This feature is of special advantage when my invention is applied to a washing machine for the reason that it compels disconnection of the agitator shaft from the power shaft before the operator can lift the cover. This prevents accidental injury to the operator by moving parts when the cover is raised to take clothes out of the tub. I do not herein claim broadly the automatic disconnection of the transmission shaft 12 from the power shaft 19 when the handle 42 is moved into unlatching position, because this feature is broadly claimed in my copending application, Ser. No. 620,101, filed April 10, 1911.

The hinged member 5 supports a central vertical shaft 51 which is shown in the drawings as the agitator shaft of a washing machine. This shaft has fixed thereto a pinion 52 which is preferably inclosed in a housing 53 secured on top of the hinged member 5. A rack bar 54 is adapted to mesh with the pinion 52 for imparting an oscillatory movement to the shaft 51 as the transmission shaft 12 is rotated. The rack 54 is connected to the crank member 13 by means of a swivel connection 55, so that the rack can move in a horizontal as well as a vertical plane. The swivel connection 55 is pivoted to the crank member 13 by means of the crank pin 14. The rack bar 54 is pivoted to the swivel connection 55 by means of the horizontal pin 56. In this way the rack bar 54 is free to swing in a horizontal plane as the crank member 13 is rotated without breaking connection with the pinion 52. At the same time the rack 54 may be readily swung about the pin 56 out of engagement with the pinion 52. The swivel connection 55 is preferably mounted loosely on the crank pin 14 so that the rack bar can be bodily removed from the crank member 13.

The vertical transmission shaft 12 has fixed thereto a clutch member 57 provided with teeth 58 adapted to interlock with the teeth 59 of the clutch sleeve 60 which is slidably and non-rotatably mounted on the shaft 12. The clutch sleeve 60 is provided with an annular recess 61 in which the free ends of a pair of arms 62 are arranged to engage. The arms 62 are fixed upon a rock shaft 63 rotatably supported in the openings 64 formed in the casting C. When the

arms 62 are rocked downwardly, the clutch sleeve 60 is moved into locking engagement with the clutch member 57. The rock shaft 63 is at its outer end provided with an arm 55 which is fixed upon the shaft by means of a set screw 66, or otherwise. The arm 65 is near its upper end provided with a slot 66 through which extends a link 67. The inner end of the link 67 is bent laterally at 68 and passed through an opening 69 in the vertical lug 70 mounted on the hinged member 5. This lug is in the drawings shown as part of one of the hinges 6. A compression spring 71 is coiled about the link 67. The inner end of the spring 71 is connected to the link 67 in any suitable manner, as by bearing against the transverse pin 72 on the link 67. The outer end of the spring 71 bears against the arm 65, 20 a disk or washer 73 being preferably interposed. The free or outer end of the link 67 is provided with a pin 74 to which is pivoted the locking member 75. This member is shaped to straddle the link 67 so that 25 the inner end thereof may rest firmly against the arm 65, as shown in Figs. 4 and 8, without danger of being forced upwardly out of locking position. When the cover or hinged member 5 is in closed position and 30 the member 75 in locking position, the arm 65 is in the position shown in Figs. 2 and 8 and the clutch sleeve 60 is in its inoperative position. When now the hinged member 5 is swung upwardly into open position, 35 the spring 71 rocks the arm 65 downwardly and with it the shaft 63 and the arms 62. Consequently, the clutch sleeve 60 is moved downwardly into operative engagement with the clutch member 57. As will presently be 40 explained, when the clutch member 60 is in operative position, it establishes connection between the transmission shaft 12 and a horizontal shaft which in the herein illustrated embodiment of my invention is the 45 wringer shaft. The closed position of the clutch sleeve 60 when the hinged member 5 is in open position, is shown in Fig. 4. When the hinged member 5 is swung down into closed position the clutch sleeve 60 is 50 automatically disconnected from the shaft 12 and the operation of the wringer shaft ceases. However, the wringer shaft may be operatively connected with the transmission shaft 12 even when the hinged member 5 is closed, by simply moving the locking member 75 upwardly into inoperative 55 position, as shown in Fig. 3. When this is done the arm 65 is thrown downwardly by the spring 71 and the clutch sleeve 60 is moved into operative position, in precisely the same manner as when the hinged member is swung upwardly. To facilitate the adjustment of the locking member 75 into and out of operative position, the same 60 may be provided with a handle piece 76

which is shown in the drawings in the form of a ring. Also, the arm 65 is at its upper end preferably provided with a handle 77 so that the arm can be easily grasped and forced away from the locking member 75 70 when it is desired to move the latter back into operative position. It will thus be seen that the clutch composed of the members 58 and 60 is controlled by the two independently operable members 5 and 75 75

I will now describe the horizontally swinging shaft and the connections between the same and the clutch sleeve 60. To the side of the support 1 is fixed a bracket indicated, as a whole by B, which comprises a 80 vertical portion 78 having a horizontal extension 79 at its upper end and a horizontal extension 80 at its lower end. The bracket B is secured to the support 1 by means of bolts 81 or other suitable fastening devices. 85 To the bracket B is pivoted the bracket B' which, like the bracket B, comprises a vertical portion 82, an upper horizontal extension 83 and a lower horizontal extension 84. The horizontal extensions of the two 90 brackets are provided with vertically aligned openings 85. Through the aligned openings of the lower extensions 80 and 84 passes the pivot bolt or stud 86. Through the aligned openings in the upper horizontal extensions 79 and 83 passes the screw threaded pivot bolt 87 on which works a thumb nut 88 for rigidly clamping the swinging bracket B' into any one of its adjusted positions. The swinging bracket B' carries a 100 suitable frame-work which has been shown in the drawings as the wringer frame-work W. The frame-work W carries the horizontal shaft 89 which extends through the opening in the bracket B'. To the outer end of the horizontal shaft 89 is fixed the bevel pinion 90 which is arranged to mesh with the bevel pinion 91 secured to the upper end of the vertical counter-shaft 92. The bevel gears 90 and 91 together with the counter-shaft 92 are preferably inclosed in a housing 93 which is provided with bearing portions 94 and 95 for the counter-shaft 92. The bevel pinion 91 is provided with a hub 110 portion 96 which is adapted to rest on the bearing 94 and thereby hold the shaft 92 suspended in the housing 93. The connected portion between the bearings 94 and 95 is not shown in Fig. 7, because the housing is shown in longitudinal cross section. The housing 93 is supported on the bracket arm 97. One end of this bracket arm extends through the head portion 8 of the casting C, as shown at 98 in Fig. 2. At an intermediate point the bracket arm 97 is 120 secured to the support 1 by means of a bolt 99, as shown in Fig. 7. The outer end of the bracket arm 97 is provided with a perforated bearing extension 100 on which rests directly the bearing portion 95 of the hous- 130

ing 93. Through the opening in the extension 100 of the bracket arm 97 passes the lower end of the counter-shaft 92. It is to be observed that the axis of the counter-shaft 92 is in vertical alinement with the axis of the pivot bolts 86 and 87 about which the bracket B' swings. Consequently, when the bracket B' is swung about its pivot the bevel gear 90 is free to roll around the associated bevel gear 91 without breaking connection therewith. To the extended lower end of the counter-shaft 92 is fixed a sprocket wheel 101. The clutch sleeve 60 has rigidly connected therewith a sprocket wheel 102. In the illustration shown in the drawings the sprocket wheel 102 is provided by forming sprocket teeth on the clutch sleeve 60. A sprocket chain 103 passes around the sprocket wheels 101 and 102 to transmit the rotation of the clutch sleeve 60 to the counter-shaft 92 and thence to the horizontal shaft 89. To provide additional steadyng means for the bracket B, the placing arm 104 is bolted to the support at 105 and passes under the lower extension of the bracket B. The pivot bolt 86 passes through the opening at the outer end of the bracing arm 104. It will be clear from the above that as long as the clutch sleeve 60 is in its upper or inoperative position, the horizontal or wringer shaft 89 is disconnected from the transmission shaft 12. When the clutch member 60 is moved downwardly either by opening the cover 5 or releasing the locking member 75, the horizontal shaft 89 becomes operatively connected with the transmission shaft 12.

The horizontally swinging shaft 89 is particularly useful when my improved gear mechanism is applied to a washing machine, in which case this horizontal shaft is the wringer shaft. When the operator wishes to wring the clothes out of the tub 1 he first unlatches the cover 5 by moving the handle 42 into unlatching position. As previously stated, this unlatching of the cover 5 automatically disconnects the transmission shaft 12 from the power shaft 19, so that there is no danger of any moving parts injuring the operator when he manipulates the cover 5. After the cover has been swung into open position, the handle 42 is turned to throw the clutch member 22 into its forward operative position, and by this position I mean that which causes the wringer shaft 89 to revolve in a forward direction to wring clothes from the tub 1 into a suitable receptacle placed at the side of the tub. It may sometimes be necessary or desired to operate the wringer mechanism at the same time that the agitator shaft 51 is operated to wash a batch of clothes in the tub. This is done by swinging the bracket B' away from the support until the wringer occupies a position substantially at right angles from

its position against the tub, as indicated in dotted lines at W' in Fig. 5. When the wringer is in this position operative connection between the wringer shaft 89 and the transmission shaft 12 is established by 70 moving the locking member 75 upwardly as seen in Fig. 3, whereby the clutch sleeve 60 is moved into operative position. The wringer may then be used to wring the clothes from one receptacle into the other, 75 while at the same time the agitator shaft 51 is being operated to wash the clothes in the tub.

The wringer may be provided with a hand wheel 106 for turning the wringer 80 backwardly, as for unwinding clothes from the wringer rolls. Of course, this backward operation of the wringer shaft takes place when the wringer shaft is disconnected from the power shaft 19.

While I have herein shown one specific embodiment of my invention, I would have it understood that changes and alterations may be made by those skilled in the art without departing from the scope of the 90 invention as defined in the appended claims.

Having thus described my invention what I claim as new and desire to secure by Letters Patent of the United States is:

1. In a mechanism of the class described, 95 the combination of a suitable support, a frame carried by said support and adapted to swing bodily in a horizontal plane, bearings in said frame, a pair of parallel roller shafts geared together and mounted in the 100 bearings of said frame, said shafts being horizontally disposed, a motor, and driving connections between said motor and one of said roller shafts arranged to maintain operative driving relation irrespective of the 105 position of said frame in its horizontal plane.

2. In a mechanism of the class described, 110 the combination of a support, a frame above said support and mounted to swing in a horizontal plane, bearings carried by said frame, parallel roller shafts arranged horizontally and supported at each end by said bearings, said shafts being geared together, 115 a pinion for one of said roller shafts, a vertical shaft, a pinion on said vertical shaft meshing with the pinion of said roller shaft, said frame being mounted to swing about said vertical shaft as an axis, and the pinion of the roller shaft rolling around the pinion of the vertical shaft but maintained at all times in mesh therewith, and means for rotating said vertical shaft to drive said roller shaft, said means for rotating said vertical 120 shaft being capable of disconnection to stop the rotary motion of the rollers at the will of the operator.

3. In a mechanism of the class described, 125 the combination of a suitable support, a frame mounted above said support, parallel

roller shafts carried by said frame and mounted to swing with said frame about a vertical axis, a vertical shaft, a bevel gear at the upper end of said vertical shaft, a 5 bevel gear for one of said roller shafts and rolling around on the gear of the vertical shaft when said frame is swung about its vertical axis, driving means for said vertical shaft including means for instantly reversing 10 the rotary movement of said roller shafts or allowing them to stop at the will of the operator.

4. In a mechanism of the class described, the combination of a vertical shaft, driving 15 means for said shaft operative to instantly start or reverse said shaft or allow said shaft to stop at the will of the operator, a beveled pinion on said vertical shaft, a bracket movable about the axis of said vertical shaft, a 20 frame carried by said bracket and having bearings, horizontal roller shafts geared to one another and supported in the bearings of said frame, and a beveled pinion on one of said roller shafts meshing with the pinion 25 of said vertical shaft and adapted to roll around said last named pinion when the roller shafts are swung about the axis of said vertical shaft, and means for securing said frame in any one of its adjusted positions. 30

5. In a mechanism of the class described, the combination of a suitable support, a bracket fixed to the side of said support near the top thereof, so that the upper portion 35 of said bracket extends above the top of the support, said bracket comprising a vertical portion having a horizontal extension at each end, said extensions being provided with vertically alined bearing openings, a second bracket pivoted in said bearing 40 openings, a horizontal shaft carried by said pivoted bracket, a pinion fixed to said shaft, a vertical shaft in alinement with the pivotal axis of said swinging bracket, a pinion arranged on said vertical shaft to mesh permanently with said first-mentioned pinion which rolls around said second pinion when the horizontal shaft is swung about its vertical pivot, and means mounted on 45 said support for actuating said vertical shaft. 50

6. In a mechanism of the class described, the combination of a suitable support, a bracket fixed to the side of said support near 55 the top thereof, so that the upper portion of said bracket extends above the top of the support, said bracket comprising a vertical portion having a horizontal extension at each end, said extensions being provided 60 with vertically alined bearing openings, a second bracket pivoted in said bearing openings, a horizontal shaft carried by said pivoted bracket, a pinion fixed to said shaft, a vertical shaft in alinement with the pivotal 65 axis of said swinging bracket, a pinion ar-

ranged on said vertical shaft to mesh permanently with said first-mentioned pinion which rolls around said second pinion when the horizontal shaft is swung about its vertical pivot, clamping means engaging both 70 brackets to hold the pivoted bracket securely in any one of its adjusted positions, and means mounted on said support for actuating said vertical shaft. 75

7. In a mechanism of the class described, 75 the combination of a suitable support, a bracket secured to the side of said support near the top thereof, so that the upper portion of said bracket extends above the top of the support, said bracket comprising a vertical portion having a horizontal extension at each end, said extensions being provided with vertically alined bearing openings, a second bracket comprising a vertical portion having a horizontal extension at 80 each end, said extensions being provided with vertically alined pivot openings, a pivot stud passing through the alined openings in the lower extensions, a second pivot stud passing through the alined openings in the upper extensions, whereby the second bracket is pivotally supported on said first-mentioned bracket and adapted to swing in a horizontal plane toward and away from the support, a horizontal shaft carried by said 85 pivot bracket, a pinion fixed to said shaft, a vertical shaft in alinement with the pivotal axis of said swinging bracket, the pinion arranged on said vertical shaft to mesh permanently with said first-mentioned pinion which rolls around said second pinion when the pivoted bracket is swung about its pivot, and means mounted on said support for 90 actuating said vertical shaft. 95

8. In a mechanism of the class described, 105 the combination of a suitable support, a bracket fixed to the side of said support near the top thereof, so that the upper portion of said bracket extends above the top of the support, said bracket comprising a vertical portion having a horizontal extension at each end, said extensions being provided with vertically alined bearing openings, a second bracket comprising a vertical portion having a horizontal extension at each end, 110 said extensions being provided with vertically alined pivot openings, a pivot stud passing through the alined openings in the lower extensions, a second pivot stud passing through the alined openings in the upper extensions, whereby the second bracket is pivotally supported on said first-mentioned bracket and adapted to swing in a horizontal plane toward and away from the support, a horizontal shaft carried by said pivoted 115 bracket, a pinion fixed to said shaft, a vertical shaft in alinement with the pivotal axis of said swinging bracket, a pinion arranged on said vertical shaft to mesh permanently with said first-mentioned pinion which rolls 120 around said second pinion when the pivoted bracket is swung about its pivot, and means mounted on said support for actuating said vertical shaft. 125

130

around said second pinion when the pivoted bracket is swung about its pivot, an adjustable nut on one of said studs to clamp the associated extensions together and thereby hold the pivoted bracket firmly in any one of its adjusted positions, and means mounted on said support for actuating said vertical shaft.

9. In a mechanism of the class described, the combination of a suitable support provided at its upper end with a hinged member which normally rests in a horizontal position, a pair of shafts carried by said support, a driving connection between said shafts, including a normally open clutch, and means whereby said clutch is automatically closed when said hinged member is swung upward, said means being adjustable by hand independently of said hinged member to close said clutch while said hinged member is in horizontal position.

10. In a mechanism of the class described, the combination of a suitable support provided at its upper end with a hinged member which normally rests in horizontal position, a pair of shafts carried by said support, a driving connection between said shafts, including a normally open clutch, a rock shaft for operating said clutch, an arm secured to said rock shaft, a rod pivoted at one end to said hinged member and the other end having a slidable connection with said arm, a compression spring mounted on said rod to bear against said arm and thereby rock said shaft to close the clutch when said hinged member is swung up, an adjustable retaining member against which said arm is adapted to bear under the action of the spring, said retaining member being movable into releasing position to permit closing of the clutch by the spring when the hinged member is down, a handle on said arm for readily moving the same against the spring and thereby permitting quick and easy adjustment of said retaining member.

11. In a mechanism of the class described, the combination of a suitable support, a casting secured at the side of said support, said casting comprising a vertical body section which terminates at its lower end in an enlargement, a transmission shaft journaled in the vertical section of said casting, a horizontal power shaft journaled in said enlargement, a driving connection between said shafts, a gear fixed to said power shaft beneath said support, a motor mounted beneath said support, and a pinion arranged on the motor shaft to mesh with said gear.

12. In a mechanism of the class described, the combination of a suitable support, a casting secured thereto, said casting being provided with a pair of vertically alined bearings and a pair of horizontally alined bearings, a shaft journaled in each pair of bearings, a driving connection between said shafts, a gear fixed to the horizontal shaft

beneath said support, a motor mounted beneath said support, and a pinion arranged on the motor shaft to mesh with said gear.

13. In a mechanism of the class described, the combination of a suitable support provided at its upper end with a hinged member which normally rests in horizontal position, a pair of shafts carried by said support, a driving connection between said shafts, including a normally open clutch, a rock shaft for operating said clutch, an arm secured to said rock shaft, a rod pivoted at one end to said hinged member and the other end having a slidable connection with said arm, a compression spring mounted on said rod to bear against said arm and thereby rock said shaft to close the clutch when said hinged member is swung up, an adjustable retaining member against which said arm is adapted to bear under the action of the spring, said retaining member being movable into releasing position to permit closing of the clutch by the spring when the hinged member is down, a handle on said arm for readily moving the same against the spring and thereby permitting quick and easy adjustment of said retaining member.

14. In a mechanism of the class described, the combination of a suitable support provided with legs, cross braces connecting said legs, a bracket extending upwardly from said cross braces, a horizontal power shaft extending beneath said support, a gear fixed upon said shaft, a frame pivotally connected with said shaft and resting on said bracket, a motor mounted on said frame, and a pinion fixed upon the motor shaft to mesh with said gear.

15. In a mechanism of the class described, the combination of a suitable support, a horizontal shaft rotatably mounted on said support and adapted to swing bodily in a horizontal plane toward and away from said support, a pinion fixed to said shaft, a vertical shaft carried by said support in vertical alinement with the pivotal axis of said horizontally swinging shaft, a pinion arranged on said vertical shaft to mesh permanently with said first-mentioned pinion which rolls around said second pinion when the horizontal shaft is swung above its vertical pivot, a motor-driven shaft mounted on said support for actuating said vertical shaft, and a hand-operated member for rotating said horizontal shaft independently of said power shaft.

16. In a mechanism of the class described, the combination of a suitable support, a horizontal shaft rotatably mounted on said support and adapted to swing bodily in a horizontal plane toward and away from the support, a pinion fixed to the shaft, a vertical shaft carried by said support in vertical alinement with the pivotal axis

of said horizontally swinging shaft, a pinion arranged on said vertical shaft to mesh permanently with said first-mentioned pinion which rolls around said second pinion 5 when the horizontal shaft is swung about its vertical pivot, a second vertical shaft journaled at the side of said support, a driving connection between said shafts, a horizontal power shaft arranged below said 10 support and adapted to be geared to said second vertical shaft, and a motor for driving said power shaft.

17. In a mechanism of the class described, the combination of a suitable support, a pair 15 of horizontal roller shafts geared together and mounted one above the other on said support, said roller shafts being relatively adjustable to change the distance from one to the other and being adapted to swing in 20 a horizontal plane, a pinion for one of said shafts, a vertical shaft carried by said support in vertical alinement with the pivotal axis of said horizontally swinging shafts, a pinion arranged on said vertical shaft to mesh permanently with said first mentioned 25 pinion which rolls around said second pinion when the horizontal shaft is swung about its vertical pivot, a motor driven shaft mounted on said support, and a driving connection between said motor driven shaft and 30 said vertical shaft.

18. In a mechanism of the class described, the combination of a suitable support, a pair 35 of horizontal roller shafts geared together and mounted on said support, said roller shafts being relatively adjustable to change the distance from one to another and being adapted to swing pivotally in a horizontal plane, a pinion for said shaft, a vertical 40 shaft carried by said support in vertical alinement with the pivotal axis of said horizontally swinging shaft, a pinion arranged on said vertical shaft to mesh permanently with said first mentioned pinion which rolls 45 around said second pinion when the horizontal shaft is swung about its vertical pivot, a second shaft journaled to said support, a driving connection between said second shaft and said vertical shaft, mechanical 50 means for reversing the direction of rotation of said first named shaft at the will of the operator, a horizontal power shaft arranged below said support and operatively connected with said second shaft, and a 55 motor for driving said power shaft.

19. In a mechanism of the class described, the combination of a suitable support, a pair 60 of horizontal roller shafts rotatably mounted on said support and adapted to swing pivotally in a horizontal plane toward and away from the support, a pinion for one of said shafts, a vertical shaft in alinement with the pivotal axis of said horizontally swinging shafts, a pinion ar-

ranged on said vertical shaft to mesh permanently with said first mentioned pinion which rolls around said second pinion when the horizontal shafts are swung about their vertical pivot, means for securing said horizontal shafts against movement about said 70 vertical axis, a horizontal power shaft arranged below said support, a motor connected to said power shaft, and power transmitting connections between said power shaft and said vertical shaft. 75

20. In a mechanism of the class described, the combination of a suitable support, a frame carried by said support and adapted to swing bodily in a horizontal plane, bearings in said frame, a pair of parallel roller 80 shafts geared together and mounted in the bearings of said frame, said shafts being horizontally disposed, and power driven connections to one of said roller shafts, said driving connections being operative irrespective of the position of said frame in its horizontal plane. 85

21. In a mechanism of the character described, the combination of a support, a power source in fixed position relatively thereto, a pair of horizontal roller shafts gears connecting said shafts together, resilient means for holding said roller shafts relative to one another, a frame supporting said roller shafts, said frame being movable outward from said support to a new position, and gear driving connections from said power source to said roller shafts, said connections being operative to drive said roller shafts either forward or backward when said frame is in either of its positions. 95

22. In a mechanism of the character described, the combination of a support, a pair of horizontal roller shafts geared together, resilient means for holding said roller shafts relative to one another, a frame supporting said roller shafts, said frame being mounted to swing to a new position, and driving connections for said shafts, said connections being operative to drive said roller shafts 105 when said frame is in its different positions, said driving connections including mechanically reversing means whereby said roller shafts may be instantly started, reversed or allowed to stop at the will of the operator. 110

23. In a machine of the class described, a frame, a vertical shaft thereon, means to drive said vertical shaft, a support adapted to swing about said vertical shaft in a horizontal plane, a pair of parallel roller shafts 120 geared together and arranged horizontally in said support, driving connections whereby said roller shafts may be driven in any position of their support relative to said vertical shaft, reversing means for reversing 125 the direction of rotation of said roller shafts.

24. In a machine of the class described, a frame, a vertical shaft thereon, means to

drive said vertical shaft, a support adapted to swing about said vertical shaft in a horizontal plane, a pair of parallel roller shafts geared together and arranged horizontally in said support, driving connections whereby said roller shafts may be driven in any position of their support relative to said vertical shaft, reversing means for reversing the direction of rotation of said roller

shafts, and means for locking said support 10 in adjustable position about said shaft.

In witness whereof, I hereunto subscribe my name this 10th day of May A. D. 1911.

HOWARD F. SNYDER.
